(57) **CLAIM**

The ornamental design for a lace tightening device dial as shown and described.

DESCRIPTION

1.1 : Perspective

1.2 : Front

1.3 : Back

1.4 : Right

1.5 : Left

1.6 : Top

1.7 : Bottom

The dial is operable with a lace tightening device and can be rotated by a user to tension a lace via the lace tightening device; the lace tightening device can be attached to an article, such as an article of footwear, in order to tighten the article via the tensioned lace; the portions illustrated by solid lines are the portions for which the claimed design is intended; any broken lines on the figures are for illustrative purposes only and form no part of the claimed design.
